United States Patent Office

Des. 214,894

Patented Aug. 12, 1969

214,894

CREMATION URN

Wesley M. Chandler, St. Paul, and Bernard T. Juba,
White Bear Lakes, Minn., assignors to Wilbert, Inc.,
Broadview, Ill., a corporation of Illinois

Filed Mar. 20, 1968, Ser. No. 11,045

Term of patent 14 years

Int. Cl. D31

U.S. Cl. D19—1

FIG. 1 is a perspective view of a cremation urn embodying our new design;

FIG. 2 is a side elevational view thereof as viewed from line 2—2 on FIG. 4;

FIG. 3 is an elevational view as viewed from line 3—3 on FIG. 4;

FIG. 4 is a top plan view; and

FIG. 5 is a bottom plan view.

The decorative finish shown only partially in FIG. 5 extends entirely across the bottom of the urn.

We claim:

The ornamental design for a cremation urn, substantially as shown and described.
